UNITED STATES PATENT OFFICE

2,446,103

LINOLEUM DISPENSER

Theodore Pettyjohn, Crosby, and Ralph T.
Stickel, Deerwood, Minn.

Application May 29, 1945, Serial No. 596,438

8 Claims. (Cl. 242—72)

1

This invention has reference to a device, the purpose of which, is to reel off and dispense desired lengths of linoleum or other material from an original factory roll.

Another object of the invention is to provide a rack for supporting a factory roll of linoleum, carpet or the like, in combination with a contractable roller upon which the dispensed goods or portion is wound whereby said portion may be easily removed.

A further object of the invention is to provide a linoleum rack having severing or cutting means including a straight edge and cutting board hingedly connected thereto.

A still further and a principal object of the invention is to provide a clamping and releasing means for the end of a length of material to be dispensed from a roll and severed, including a slatted roller a slidable disk expansion member operating in inclined grooves in the slots thereof.

Another object of the invention is to provide a linoleum dispenser in which a slatted drum expandable means for the slats and automatic means for the retraction of the slats to clamp and release the end of a strip thereof for dispensing any length and cutting off the same.

Other features and advantages will become more readily apparent from the following description and the accompanying illustrative drawings in which:

Figure 1 is a front elevational view of our device.

Figure 2 is a broken away end view thereof.

Figure 3 is a sectional view taken on line 3—3 of Figure 1.

Figure 4 is a sectional view taken on line 4—4 of Figure 3.

Figure 5 is a detail elevational view of an expansion device.

Figure 6 is a detail of a drum operating assembly, and

Figure 7 is a detail of a bearing member.

In the drawings illustrating our invention and in the specification to follow the same reference characters are used to indicate the same elements throughout.

The reference character 10, indicates our linoleum dispensing rack, the posts 11 and 12, carrying the transverse bars 13, forming the rack are held in upright position by brace legs 11' or in any desired manner. The members 11 and 12, are provided with aligning inclined slots 14 and 15, to receive a pole P upon which a factory roll of linoleum is supported.

The principal features of our invention, how-

2

ever, is the expandible drum 16, and its associated elements, which will now be detailed. This drum includes a shaft 17, upon which is keyed at suitable intervals externally screw threaded collars 18, upon which the internally threaded hubs 19, of the disks 20, operate, the peripheries of which are provided on one side with bevels 21, and on the other side with relatively narrow bevels 22. The bevels 21, slidably seat upon the inclined walls 23, of grooves 24, provided in the inner surfaces 25, of the spaced longitudinal slats or bars 26 shown as three in number, and a single slat or bar 26' at the top diametrically opposite the lower bar 26 and made narrower as shown in Fig. 3, which form the periphery of the drum or roller 16. The other lesser inclined wall 27, of the grooves 24, are adapted to be engaged by the bevels 22, of said disks 20, and form stops for the further movements of said disks.

Also supported at intervals upon shaft 17, are the bearings 28, of upright bolts or arms 29, having adjustment nuts 30, screwed thereon and upon which seat the flange 31, of an angle plate 32, which plate is secured in place on the members 29, by retainer nuts 33. The reversed horizontal flange 34, of plate 32, together with the upper surface 35, of member 26', form opposing jaws between which the transverse edge 36 of a roll of linoleum 37, may be clamped.

The opposing members 26 and 26', are held into frictional engagement with the peripheries of the disks 20, by means of contraction springs 38, the ends 39 and 40, being secured to the members 26 and 26', respectively.

The end 41, of shaft 17, is rotatably mounted in the bearing 42, in the member 11, while its other end 43 is supported in a bearing 44, seated in an inclined slot 45, of member 12. The shaft 17, is rotatable by means of a crank handle 46, and when rotated in one direction and the members 26, held against movement, the screw collars 18, will draw the disks 20, up the inclines 23, pushing all members, slats or bars 26 outwardly, thus expanding the diameter of drum 16. This action will cause the member 26', to move against flange 34, of the angle rail 32, and thus tightly grip the edge 36, of the linoleum 37. After this is accomplished further turning of the crank while allowing drum 16 and slats or bars 26 thereof to turn with the shaft 17, will rotate the drum and thereby wind the linoleum off of the roll 37, and onto the drum 16.

When the required strip of linoleum has been rolled onto the drum 16, the cutting board 47, supported on the arms 48 and 49, pivoted to the

rack at 50, is swung up upon the rolled linoleum, as indicated in Figure 2, then a straight edge 51, is swung down over the board 47, whereby a knife K, may be operated against said straight edge to sever the linoleum from its original roll 31. The straight edge 51, is one flange of an angle plate, the other flange 52, of which is bolted to arms 53, pivoted at 54, to members 11 and 12. When crank 46, and shaft 17, are reversed, the disks will slide into slots 24, permitting the springs 38 to retract members 26, whereby the linoleum on the drum 16, may be readily removed, such retraction releasing the inner edge of the linoleum from said clamp members 26' and 34.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described our invention that which we claim as new and desire to procure by Letters Patent is:

1. In a device as described, a slatted drum including slidable disks adapted to expand the diameter of the drum, means adapted to contract the drum, including springs connecting the slats and normally contracting the drum and slide said disks, a rack supporting the drum, and clamping means carried by the drum and actuated by the disks to clamp and release one end of the material to be wound on the drum.

2. In a device as described, a roll, a rack rotatably supporting the roll, a slatted drum including slidable disks adapted to expand the diameter of the drum, means adapted to contract the drum including springs connecting the slats and normally contracting the drum and slide said disks, said rack rotatably supporting the drum, a straight edge having side arms and clamping means carried by the drum and axis thereof and actuated by the disks to clamp and release one end of the material to be wound on the drum and severed.

3. In a device as described, a roll, a slatted drum including slats, means connecting said slats to draw the same together to contract the drum, disks longitudinally movable on the axis of the drum to engage the slats, coacting means between the disks and slats to cause said slats to move outwardly and adapted to permit inward movement thereof under the contracting means, a straight edge having arms pivotally supported, a rack supporting said arms, drum and roll, and a cutting board having arms pivoted to the rack, said straight edge adapted to swing over the roll to rest on the cutting board.

4. In a device as described, a roll, a slatted drum including slats, means connecting said slats to draw the same together to contract the drum, disks shiftably mounted on the axis of the drum to engage the slats, coacting means between the disks and slats to cause said slats to move outwardly and adapted to permit inward movement thereof under the contracting means, a straight edge having arms pivotally supported, a rack supporting said arms, drum and roll, and a cutting board having arms pivoted to the rack, said straight edge and board adapted to swing over the roll with the straight edge resting on the board whereby the material may be severed.

5. In a device as described, a rack, a roll rotatably supported by the rack, a slatted drum having its axis rotatably supported by the rack and including longitudinally shiftable disks thereon having bevelled edges, said drum including slats having oppositely inclined grooves engaged by the peripheral edges of the disks to move the slats outwardly upon shifting the disks in one direction and adapted to permit said slats to move inwardly upon shifting the disks in the opposite direction, springs connecting the slats to contract the drum, and clamping means carried by the drum and axis thereof and actuated by the disks to clamp and release an end of material to be wound on the drum and cut.

6. In a device as described, a rack, a roll rotatably supported by the rack, a slatted drum having its axis rotatably supported by the rack and including longitudinally shiftable disks thereon having bevelled edges, said drum including slats having oppositely inclined grooves engaged by the peripheral edges of the disks to move the slats outwardly upon shifting the disks in one direction and adapted to permit said slats to move inwardly upon shifting the disks in the opposite direction, springs connecting the slats to contract the drum, and clamping means carried by the drum and axis thereof and actuated by the disks to clamp and release an end of material to be wound on the drum and cut, and including a fixed member on the drum and a movable member expanded and contracted by the disks to grip and release the end of a roll of material to be dispensed and cut off.

7. In a device as described, a rack, a slatted drum rotatably supported by the rack and having a shaft provided with threaded sleeves, a roll rotatably supported by the rack, said slatted drum including shiftable disks having interiorly threaded hubs engaged on the threaded sleeves and having bevelled peripheral edges sloping in opposite directions, certain of the slats having oppositely inclined grooves engaged by the peripheral edges of the disks, springs connecting the slats and normally contracting the drum, arms engaged on the shaft, said shaft rotating independently of the arms, one of the slats being positioned adjacent the arms, a clamping strip carried by the arms adjacent to the slat, whereby one end of the material to be wound from the roll onto the drum may be clamped between said slat and strip, upon shifting the disks longitudinally of the shaft, and means on the rack for severing the material transversely lengthwise of the drum and roll.

8. In a device as described, a rack, a slatted drum rotatably supported by the rack and having a shaft provided with threaded sleeves, a roll rotatably supported by the rack, said slatted drum including slidable disks having interiorly threaded hubs engaged on the threaded sleeves and having bevelled peripheral edges sloping in opposite directions, certain of the slats having oppositely inclined grooves engaged by the peripheral edges of the disks, springs connecting the slats and normally contracting the drum, arms engaged on the shaft, said shaft rotating independently of the arms, one of the slats being positioned adjacent the arms, a clamping strip carried by the arms adjacent to the slats, whereby one end of the material to be wound from the roll onto the drum may be clamped between said slat and strip, upon shifting the disks longitudinally of the shaft, a straight edge having side

arms pivoted to the rack at the sides thereof and adapted to swing over and away from the roll, and a cutting board having side arms pivoted to the rack to swing over the roll, said straight edge adapted to swing over the board to rest thereon and form a knife guiding means for severing the material from the roll in desired lengths wound on the drum.

THEODORE PETTYJOHN.
